UNITED STATES PATENT OFFICE.

JAMES F. MCELROY, OF ALBANY, NEW YORK, ASSIGNOR TO THE CONSOLIDATED CAR-HEATING COMPANY, OF SAME PLACE.

CAR-BRAKING MECHANISM.

SPECIFICATION forming part of Letters Patent No. 644,444, dated February 27, 1900.

Application filed October 22, 1898. Serial No. 694,271. (No model.)

To all whom it may concern:

Be it known that I, JAMES F. MCELROY, a citizen of the United States of America, and a resident of Albany, in the county of Albany and State of New York, have invented certain new and useful Improvements in Car-Braking Mechanism, of which the following is a specification.

My invention relates to car-braking mechanism; and the object of my invention is to provide a mechanical brake adapted to be used on street-cars so constructed that the slack of the brake-chain may be taken up quickly and the brake-shoes brought in contact with the wheels during a partial revolution only of the brake-handle. I attain this object by means of the mechanism illustrated in the accompanying drawings, in which—

Figure 1 is a perspective taken from the under side of the car-platform, showing the position of the operating parts after the slack has been taken up. Fig. 2 is a plan showing its position before the brake has been operated. Fig. 3 is a view of the brake-staff and supporting device, partly in section.

Similar letters refer to similar parts throughout the several views.

The brake-staff A is provided with a handle B and supported on the platform C of the car, through which platform the brake-handle passes, by means of a suitable casting D or in any convenient manner, to which casting D is preferably attached a cam-shaped block E. To the brake-staff is secured or constructed integral therewith an arm F, carrying pivoted thereto a flying lever G, to one end of which is secured the brake-chain H. The flying lever G has a curved surface g, adapted to engage with the cam-shaped block E. I also provide a stop-lug J, preferably on the under side of the flying lever G, which will limit the movement of the flying lever by coming in contact with the brake-arm F when the slack has been taken up and the chain engages with the brake-staff A and which lug serves to hold the flying lever away from the brake-arm, so that the flying lever may be revolved and the brake-chain wound onto the brake-staff without interference with the cam-block. The cam-block E is preferably so constructed that there shall be a lever-stop con-

sisting of a recess or opening at e, which is preferably provided with a curved surface, the curve being the arc of a circle of which the fulcrum of the flying lever is the center, 55 to allow one end of the flying lever G to enter when the brake is off, at which time it will assume the position shown in Fig. 2, the cam portion of said cam-block so arranged in contour that when the brake is operated to 60 take up the slack the lever will be guided thereby, so as to throw the brake-chain-carrying end of the flying lever forward of the brake-staff until the lug J comes in contact with the brake-arm. As thus arranged when the 65 brake-handle is operated for the purpose of setting the brakes the flying lever will move in the direction shown by the arrow, guided by the cam-block, until the end of the flying lever to which the brake-chain is attached is 70 forward of the brake-staff and also passes the fulcrum of the said lever, when the pull on the chain will force the end of the lever carrying the chain toward the brake-staff, bringing the chain in contact therewith and the 75 lug J in contact with the brake-arm F, which will prevent the flying lever from coming in contact with the cam-block during further revolution of the brake-staff in winding up the brake-chain. When the brake is thrown 80 off, the chain will unwind from the brake-staff until it reaches the position shown in Fig. 1, when a further movement in the direction of unwinding causes the lug to break its contact with the brake-arm F and the flying 85 lever to assume the position shown in Fig. 2.

About one-eighth of a revolution of the brake-handle will bring the chain in contact with the brake-staff and take up the slack, bringing the brake-shoes in contact with the 90 wheels. Further revolution will wind the chain about the brake-staff and set the brakes.

What I claim as my invention, and desire to secure by Letters Patent of the United States, is—

1. A mechanical brake, consisting of a rotary brake-staff, an arm formed integral therewith or secured thereto, a lever pivoted upon said brake-arm, a brake-chain secured to said lever, with a cam-block arranged to guide 100 said lever, substantially as described.

2. In a mechanical brake, a rotary brake-

staff, an arm rigidly secured thereto, a lever pivoted to said arm, with a brake-chain attached to said lever, substantially as described.

5. 3. In a mechanical brake, a brake-staff, a brake-chain, a flying lever pivotally supported to said brake-staff or a projection thereon, said brake-chain connected with said flying lever near one end of the same, a cam-block, 10 all so arranged and connected up that a partial revolution of the brake-staff will cause the end of the flying lever to which the chain is attached to move forward of the brake-staff, guided by the cam-block, until the brake-chain passes the fulcrum of the flying lever, when the brake-chain will come in contact with the brake-staff, with a means for locking the flying lever out of contact with the cam-block during the further revolution of 15 the brake-staff in the direction of winding the brake-chain thereon.

4. A mechanical brake, consisting of a flying lever suitably supported by a brake-staff and attached near one end to a brake-chain, 25 a cam-block arranged to guide said flying lever, with a brake-staff and a means for locking said flying lever out of contact with the cam-block after the revolution of the brake-handle has brought the chain in contact with 30 the brake-staff.

5. A mechanical brake, consisting of a brake-staff, a brake-chain, a flying lever pivotally mounted on a projection on the brake-staff, said chain connected to said flying lever, a cam-block, a means for automatically 35

locking said flying lever when the brake-chain is brought in contact with the brake-staff during the revolution of the brake-staff, in such a manner that the cam-block will not interfere with the flying lever during the further 40 revolution of the brake-staff in winding up the brake-chain.

6. In a mechanical brake, a brake-staff, a chain, a flying lever pivotally secured to a projection on the brake-staff, said chain connected to said flying lever, a cam-block arranged to guide said flying lever, a lever-stop with which said flying lever engages when the chain is unwound, and means for locking the flying lever during the winding of the 45 chain on the brake-staff in such a manner that the flying lever cannot engage with said lever-stop except when the chain is unwound.

7. In a mechanical brake, a brake-staff, a brake-chain, a flying lever pivoted to a projection on the brake-staff and attached to said brake-chain, a cam-block arranged to guide said flying lever, a lever-stop consisting of a curved recess the surface of which is the arc of a circle of which the fulcrum of 50 the flying lever is the center, so arranged that when the chain is unwound, the end of the flying lever will come in contact with said stop.

Signed by me at Albany aforesaid this 18th 65 day of October, 1898.

JAMES F. McELROY.
